UNITED STATES PATENT OFFICE.

RALPH CHARLES STIEFEL, OF ELLWOOD CITY, AND JOHN H. NICHOLSON, OF PITTSBURG, PENNSYLVANIA, ASSIGNORS TO THE STANDARD SEAMLESS TUBE COMPANY, OF PENNSYLVANIA.

CRANE FOR PICKLING-TANKS, &c.

SPECIFICATION forming part of Letters Patent No. 681,275, dated August 27, 1901.

Application filed June 12, 1900. Renewed June 10, 1901. Serial No. 63,975. (No model.)

To all whom it may concern:

Be it known that we, RALPH CHARLES STIEFEL, of Ellwood City, and JOHN H. NICHOLSON, of Pittsburg, Pennsylvania, have invented certain new and useful Improvements in Cranes for Pickling-Tanks and other Uses, of which the following is a description, referring to the accompanying drawings.

The invention is applicable to a great many uses, but has been found especially useful as applied to cranes or hoisting mechanism for crates which contain tubes and which are lowered into and raised from the pickling solutions by which the oxid or scale is removed from the tubes.

It has been customary to place a number of tubes in a suitable carrier or crate in a horizontal position and then by means of a crane to carry the crate to the pickling-tank and lower it bodily into the tank. When the pickling has been accomplished, the crate is elevated and transported to the draw-benches or desired point of destination for the next step in the process of manufacturing the tubes. It is desirable when hoisting the tubes out of the tank to incline them slightly, so that the solution within the tube may be discharged from the interior of the tubes completely and without unnecessary delay.

It is the object of the present invention to produce hoisting mechanism that will accomplish this effect automatically in the operation of hoisting the crates. Preferably the crate is hung by two or more chains at its respective ends, and in the operation of the improved mechanism it is hoisted from a horizontal position within the tank to a position above the surface of the solution, where it assumes an inclination of about ten degrees, which is found to be a sufficient angle to allow the solution to discharge freely from the interior of the tubes. A greater angle endangers the slipping of the tubes themselves upon the crate. On being hoisted farther the crate preferably reassumes a horizontal position.

The invention is capable of many embodiments.

In the accompanying drawings three differ-

ent modes of carrying out the invention are shown.

Figure 1 is a side elevation looking parallel with the rails and the travel of the crane and showing the crates suspended at a slight inclination above the pickling-tank. Figs. 2 and 3 are a side elevation and plan view of certain details. Figs. 4 and 5 are corresponding side and end elevations of modified details of the hoisting mechanism. Figs. 6 and 7 are corresponding views of another modification.

Throughout the figures like letters of reference indicate the same or similar parts.

In Figs. 1, 2, and 3 the traveling bridge-crane *a* is supported on rails *b* and carries the crate or carrier *c* for the tubes, bars, or other articles to be pickled. The crate *c* is shown immediately above the pickling-tank *d*. The hoisting mechanism of the crane may be actuated by an electric motor in a suitable casing *f* or in any other convenient manner. Two or more chains *g* *g'* support the crate. Preferably there will be two chains *g* *g'*, secured near the respective ends of the crate, as shown. One of the chains, *g*, may be wound in a spiral groove *h* upon a cylindrical drum *j*, mounted upon a power-driven shaft *k*. The other chain, *g'*, will be wound upon the same drum *j*; but in order to vary the speed of its lifting effect upon the crate *c* relatively to the lifting effect of the chain *g* a movable idler-wheel *l* is provided. The chain *g'* runs over this idler *l* and past the guide-pulley *m*, and by the movement of the idler *l* toward and from the drum *j* a retardation or acceleration of the hoisting effect of the chain *g'* relatively to that of the chain *g* is produced by reason of the increase or decrease of the length of chain extending around the idler *l* between the drum *j* and the idler *m*. This movement of the idler *l* is effected by a connecting-rod *p*, secured eccentrically by a wrist-pin *q* to the gear-wheel *r*, supported on a fixed center and meshing with the spur-wheel *s* on the shaft *k*. The wrist-pin *q* may be readily adjustable in a radial slot in the wheel *r*, as indicated in Fig. 2 of the drawings. By supporting the idler *l* so that

it may move freely horizontally—as, for instance, by a suspended link, as shown in Fig. 2—under the influence of the connecting-rod *p* and by proportioning the gears *r* and *s* so that the gear *r* makes a complete revolution during the hoisting of the crane from its uppermost positions the chains *g* *g'* may be made to raise the crate *c* from a horizontal position to the inclined position shown in Fig. 1 and subsequently at the highest position to suspend the crate *c* horizontally.

In Fig. 2 the different positions of some of the parts are shown in dotted lines, and from these the operation will be apparent. In the highest or the lowest position the wrist-pin *q* is at *q'*, Fig. 2, and the idler *l* is at *l'*. If now the chains *g* *g'* are unwound, so as to lower the crate *c*, the drum *j'* and the wheel *r* turn as indicated by the arrows in Fig. 2, causing the idler *l* to move toward the right-hand of the figure to the position shown in the full lines in Fig. 2 and tending thereby to shorten chain *g'*, so that the right-hand end of the crate will be lowered less than the left-hand end, as seen in Fig. 1. The inclination becomes greatest when the wrist-pin *q* reaches the position *q''* and the idler *l* reaches *l''*. When the wheel *r* has made a complete revolution, the crate *c* should be at its lowermost position and will of course be again horizontal. In hoisting the reverse action takes place, the right-hand end of the crate being elevated more rapidly, so as to pass into the intermediate position. (Shown in Fig. 1.)

When so inclined, the tubes discharge the solution from their interiors in a few seconds, after which the hoisting is resumed and the crate brought to its uppermost level position ready for transportation by the crane *a*.

In Figs. 4 and 5 the mechanical embodiment of the invention is different. Ropes *g''* and *g'''*, carrying the hoisting-hooks, are wound in spiral grooves on the drum *h'*. The rope *g'''* runs over a fixed idler *m'*. The spiral groove on which the rope *g'''* is wound is not concentric with that of the ropes *g''*, so that an uneven hoisting of the crate will be produced and the crate will consequently be inclined when hoisted part way. In other respects the operation of the devices shown in Figs. 4 and 5 is similar to that already described.

In Fig. 7 another modification is shown for

producing the uneven hoisting of the two chains *g^{iv}* and *g^v*. Here both the chains are wound upon cylindrical drums *h'''*, one of which is driven by the shaft *k'''*. The other is driven through the chain of elliptical gears *t'* and spur-gears *u*, *u'*, *u''*, and *u'''*, as shown. Consequently in a half-revolution of the gear *u'* the gear *u''* will likewise make a half-revolution, but in doing so will turn at first more slowly, so as to lag behind the gear *u'*, and subsequently will turn faster, so as to complete the half-revolution with the gear *u'''*.

The invention is capable of a great many modifications without departing from the essential principles. The foregoing description, however, sets forth three preferred embodiments of it, and from these the general nature of the invention will be fully apparent.

We claim and desire to secure as the characteristic and distinguishing features of the invention the following:

1. In a hoisting and lowering apparatus for crates and the like, in combination the device of two or more co-operating hoisting connections and means for actuating the said connections unequally, and inclining the crate at an intermediate position when partly elevated, and restoring the said crate to a horizontal position at the highest and lowest positions, substantially as set forth.

2. In combination with a crate or carrier and a crane for hoisting and transporting it, hoisting mechanism and connections therefrom adapted to be secured to two or more points of the said crate, including means for elevating one portion of the crate more rapidly than other portions at one part of the movement and more slowly at another part of the movement, substantially as set forth.

3. In combination with a horizontal pickling-tank, a pickling-crate therefor, power-actuated mechanism for immersing the crate horizontally in the said tank and elevating it at an inclination, a movable crane, said mechanism being mounted on the said crane, substantially as set forth.

Signed this 16th day of May, 1900.

RALPH CHARLES STIEFEL.
JOHN H. NICHOLSON.
